UNITED STATES PATENT OFFICE

157,862

TELEVISION LENS PROJECTION UNIT

William Anthony Greenwood, Barnet, and William Liddell, Hook, Surbiton, England, assignors to Imperial Chemical Industries Limited, a corporation of Great Britain

Application July 11, 1949, Serial No. 3,836

Term of patent 14 years

(Cl. D26—14)

To all whom it may concern:

Be it known that we, William A. Greenwood and William Liddell, subjects of the King of England, residing at 10 Connaught Road, Barnet, Hertfordshire, England, and 98 Cheshire Gardens, Hook, Surbiton, in the county of Surrey, England, respectively, have invented a new, original, and ornamental Design for Television Lens Projection Unit, of which the following is a specification, reference being had to the accompanying drawings, forming a part thereof, and wherein

Figure 1 is a perspective view of a television lens projection unit, showing our new design;

Figure 2 is a side elevational view thereof; and

Figure 3 is a sectional view of the top portion of the structure taken along the line 3—3 of Figure 2.

We claim:

The ornamental design for a television lens projection unit, substantially as shown.

WILLIAM ANTHONY GREENWOOD.

WILLIAM LIDDELL.
